Miss B. Wible,

By Geo. D. Whittney,
Attorney.

UNITED STATES PATENT OFFICE.

MILO BROWN WIBLE, OF ARCATA, CALIFORNIA.

SWINGING GATE.

SPECIFICATION forming part of Letters Patent No. 423,504, dated March 18, 1890.

Application filed November 12, 1889. Serial No. 330,034. (No model.)

To all whom it may concern:

Be it known that I, MILO BROWN WIBLE, a citizen of the United States, residing at Arcata, in the county of Humboldt and State of California, have invented certain new and useful Improvements in Swinging Gates; and I do declare the following to be a full, clear, and exact description of the invention, such as will enable others skilled in the art to 10 which it appertains to make and use the same, reference being had to the accompanying drawings, and to the letters of reference marked thereon, which form a part of this specification.

15 My invention relates to gates, and especially to swinging gates, which are adapted to be opened from either side by a person approaching them in a vehicle or on horseback.

The invention resides in certain improvements in the automatic latches and the mechanism for operating the gate, as hereinafter described, and particularly pointed out in the claims.

20 In the drawings, Figure 1 is a perspective view of my gate represented in a closed position. Fig. 2 is a modified form of yoke.

The gate A is preferably composed of metal tubes *a*, united by suitable couplings *a'*, which form a light but strong and durable structure. It is hinged to the gate-post B by means of a pintle at its lower corner and a pintle *a*² at its upper corner, the former entering a socket *b* and the latter projecting up through a hole *c* in the yoke C, which is suitably pivoted on a stud *b'*, so as to be rotatable in a horizontal plane. The yoke is preferably diamond-shaped, as shown, with its longer axis transverse to the plane of the gate when closed. The pivot-hole for the stud *b'* is substantially at the center of the diamond, the hole *c* being at one side of the pivot and in the line of the minor axis. At each end of the yoke is an upright pin *c'*, and at the corner opposite the hole *c* is another upright pin *c*².

Cords or chains D are attached to the pins *c'* and then led behind the pin *c*², and thence to latch-posts E, set in the ground at a distance from the fence equal to the length of the gate. An arm *e* near the top of each post supports a pulley E', over which the cord D preferably passes. On the end of each cord is a handle D', which may be weighted.

The cord may run to a separate post or to a tree conveniently situated.

The gate is provided with a pivoted latch 55 F, adapted to play vertically in a guide *a*³. The gate-post G is provided with an improved catch to engage with said latch when the gate is shut. A plate H is secured to the post, and, if desired, additional posts G' may be erected 60 on each side of the gate-post to afford a firmer support for the plate. Formed on or attached to the upper part of the plate are two outwardly-projecting flanges or ribs *h*, which are inclined downwardly from each end of the 65 plate toward the middle thereof. The inner ends of the flanges do not meet by three or four inches, leaving an open space between them.

Pivoted to the plate under each flange is a 70 dog *h'*, whose outer end or tail is heavier than the nose, which is thereby held normally in contact with or near to the under side of the flange adjacent to its inner end. The upper edge of each dog slants upwardly toward the 75 nose, so that the space between the flange and the dog is V-shaped. The plate is arranged at such a height from the ground that when the gate is in a closed position the end of the latch F will lie between the ends of the two 80 dogs and their overhanging flanges, as shown.

On each latch-post E is fastened a plate I, having a single overhanging flange *i* and dog *i'*, similar to those on the plate H, and adapted to be engaged by the latch F when the gate 85 is opened. A stop-flange *i*², against which the latch strikes, prevents the gate from swinging too far open. When closed, one of the dogs *h'* serves as a stop to prevent the gate from swinging past the post G.

90 The operation is as follows: The gate being shut, as shown, a pull on the cord D turns the yoke C on its pivot, thereby conveying the pintle *a*² toward that side of the gate away from the operator and back toward the 95 line of the posts E E. This tilts the gate over slightly and lifts the free end of it far enough to raise the latch F up through the space between the ends of the flanges. The tilting tends to swing the gate open, since its tendency is always to assume a position in the plane passing through the three pivots *a*² *b* *b'*. As soon as the latch F is lifted above the flange *h* it no longer opposes the inclina-

tion of the gate to swing open, and as the gate passes by the plate H the latch rides up over the inclined flange h , dropping to its normal position when the plate has been 5 cleared. The inertia of the gate carries it into line with the post E, upon reaching which the latch F strikes the dog i' and rides up its back until it strikes the under side of the flange i , when the nose of the dog 10 is forced down and the latch passes through between the dog and the flange and abuts against the stop-flange i^2 . The instant it leaves the dog the latter resumes its normal position and prevents the gate from swinging 15 to again. The yoke, being free to turn on its pivot, remains with its minor axis in the plane of the gate. When the operator has passed through and wishes to shut the 20 gate, he gives a pull upon the cord at the post to which the gate is locked open, turning the yoke back to the position shown in the drawings and causing the latch to be lifted from between the dog i' and the stop-flange i^2 and the gate to be swung into a 25 closed position, where it automatically latches itself, as before.

It will thus be seen that my gate can be automatically unlatched from the gate-post 30 G and swung open or released from the posts E and closed by simply pulling on the cord D, and that in either case the automatic catches will hold it in the position to which it is swung. The pivoted latch F permits the gate to be 35 opened by hand without lifting it or tilting it, and the overhanging flanges partially protect the dogs from the weather. The upright pins $c' c^2$ allow the cords D to have considerable range of movement vertically, so that the gate can be operated perfectly well on a 40 hill, where one post E must be set higher than the fence and the other post lower.

In some cases, as with a light gate, the yoke may be provided with downwardly-projecting lugs or fingers C', which will engage with 45 the top rail of the gate when the yoke has made about a quarter of a revolution and positively throw the gate in the direction in which the yoke is turned.

Having thus described my invention, what I

claim, and desire to secure by Letters Patent, 50 is—

1. The combination, with a gate having an upwardly-extending-pintle a^2 , of a yoke C, pivotally mounted on the gate-post, having a hole to receive said pintle and three upright pins $c' c^2$, arranged substantially as set forth, and cords D, attached to the pins c' and crossing at the rear of the pin c^2 , substantially as described. 55

2. The combination, with a gate having the upper pintle a^2 , of a yoke C, pivotally mounted on the gate-post, having a hole to receive said pintle, and provided with two downwardly-projecting fingers C', adapted to engage with the top rail of the gate, substantially as described. 60

3. The combination, with the plate H, provided with the two inclined flanges h , having an open space between their inner ends, of the dogs h' , pivoted to the plate below the flanges and having their noses adjacent to the inner ends of said flanges, substantially as described. 70

4. The combination, with a gate having a pivoted latch, of means for tilting the upper pintle of the gate to one side and to the rear and thereby raising the front end of the gate, a catch provided with a dog and a stop, between which the latch normally rests, and an inclined flange overhanging the dog and up 80 which the latch will ride when the gate is tilted and lifted, substantially as described. 75

5. The combination, with a gate having a pivoted latch F, of a catch consisting of a downwardly-inclined flange and a dog pivoted below the flange and inclined upwardly toward it, the latch being adapted to enter between the flange and the dog and force them apart when locking and to ride up over the inclined flange when unlocking, substantially 85 as described. 90

In testimony whereof I affix my signature in presence of two witnesses.

MILO BROWN WIBLE.
